UNITED STATES PATENT OFFICE.

WILLIAM P. WHITTINGTON, OF INDIANAPOLIS, INDIANA.

VACUUM SYSTEM.

Application filed March 18, 1925. Serial No. 16,429.

My invention pertains to the withdrawal of air and water or the like by vacuum action from steam or hydraulic systems and more particularly to heating systems, fed by steam or vapor; and consists substantially in the construction, combination and arrangement of parts hereinafter set forth and pointed out more particularly in the claims.

An object of my invention is to provide 10 a vacuum pump, the capacity of which is automatically varied with the conditions under which said mechanism is fed.

It is a primary object of my invention to provide a vacuum pump mechanism having 15 a plurality of vacuum operated outlet valves in communication with the discharge of said mechanism, the vacuum operating instrumentalities of said valves being in communication with the incoming conduit 20 of said mechanism, and adapted to respond to different vacuum tensions, whereby over feeding of said mechanism will correspondingly open one or more of said valves, and under feeding will close one or more of said 25 valves.

It is also an object of my invention to provide a vacuum pump mechanism having primary and secondary pumping means, with primary and secondary condensing 30 means adapted to feed said pumping means, respectively; a plurality of vacuum operated outlet valves in communication with the discharge of said secondary pump means, the vacuum operating parts of said 35 valves being adapted to respond to different degrees of vacuum and being in communication with the inlet of the primary condenser, whereby the outlet of the secondary pump means is controlled; and a 40 jet means operated by the discharge of the secondary pump means, said jet means being fed from the primary condenser and adapted to discharge into the secondary condenser.

It is a further object of my invention to provide a vacuum pump mechanism having primary and secondary pumping means, with primary and secondary condensing means 45 adapted to feed said pumping means, respectively; a number of vacuum operated outlet valves in communication with the discharge of said secondary pump means, the vacuum operating parts of said valves being adapted to respond to different degrees of 50 vacuum and being in communication with

the inlet of the primary condenser, whereby the outlet of the secondary pump means is controlled; and separate jet means operated by the different discharges of said outlet valves, said jet means being fed from the 60 primary condenser and adapted to discharge into the secondary condenser, when brought into use by their aforesaid respective vacuum operated parts.

The above and other objects are attained 65 by the structure illustrated in the accompanying drawings, in which: Figure 1 is a fragmentary side elevation and Fig. 2 is a fragmentary plan view.

Similar characters of reference designate 70 similar parts throughout the several views. Referring to Fig. 1, the numeral 1 designates what I call the primary pump, which is fed from the lower region of the primary condenser 2 by means of the conduit 3. The 75 discharge conduit 4 of said pump leads preferably to a heating boiler means (not shown), as used, in heating systems for residential and business buildings or the like. The numeral 5 designates the return conduit 80 from such heating system, and communicates mainly with the primary condenser 2. Said return conduit, primary condenser and the primary pump, etc., may be said to comprise a somewhat constant pressure and 85 vacuum force means for causing the normal circulation of such heating system. For the purpose, however, of providing for the different degrees of suctions required on account of varying conditions in 90 the heating system, as understood by those familiar with the art, I have provided in conjunction with said primary pump and primary condenser, respectively, a secondary pump 6 and a secondary condenser 7, which 95 receives its water or vapor contents from the primary condenser 2, as will be understood, and may be said to more properly operate as a cooling means for the discharges from said primary condenser. The 100 discharge conduit 8 of the secondary pump 6 has communication with the vacuum operated valves 9, 10, 11, and 12, said valves being conveniently arranged in series or in successive arrangement with each other, it being understood, however, that said valves may be also connected to separate branches leading from the discharge conduit 8, whenever desired. Said valves are conveniently 105 operated by the diaphragm operated mecha- 110

nisms 13, 14, 15 and 16, respectively, although dash pot, slide valve, or other vacuum operated mechanisms may be utilized in the operation of said valves, as desired. Said 5 vacuum operated mechanisms communicate with the return conduit 5 by means of the conduit 17. Said valves are adapted to discharge into the conduits 18, 19, 20 and 21, respectively, which lead to the jets 22, 23, 10 24 and 25, respectively, and operate same. The intakes 26 of said jets are in communication with the primary condenser 2, the motive stream of said injectors being directed from the discharges of the aforesaid valves 15 by means of the conduits 27 to the nozzles 28 of said injectors, and said jets thus serve to draw the vapor, air etc. from said primary condenser, the water elements tending to settle in said secondary condenser the same 20 as in said primary condenser, while the air and uncondensed vapor may discharge thru the vent 29. In this way the secondary pump 6 is conveniently fed with water, which settles in the lower region of said 25 secondary condenser, the conduit 30 serving to suitably communicate said secondary condenser with the intake of said secondary pump.

The above mentioned vacuum operated 30 mechanisms 13, 14, 15 and 16 are adjusted by means of springs 31, which are adapted to respond to different degrees of vacuum, whereby under certain conditions all of the valves 9, 10, 11 and 12 will be closed and 35 under certain other conditions all of said valves will be open, it being understood that any number of said valves may be automatically brought into use in accordance with the degrees of vacuum in said return conduit. When, therefore, the degrees of vacuum in the return conduit 5 is reduced by 40 conditions in the heating system (not shown), the primary pump 1 does not have sufficient suction capacity to keep the degree of vacuum in said return conduit at a 45 desired degree and the said vacuum operated mechanisms are adjusted so that as the degree of vacuum becomes less, said mechanisms yield to their respective springs, which 50 opens the respective valves, by which arrangement the aforesaid jets are brought into use, and being fed from the primary condenser 2 by means of the conduit 32, as 55 above mentioned, tend to combine the capacity of said secondary pump with said primary pump automatically.

Check valves 33 are provided to unite the conduit 32 with the said jets, to prevent reversing of the movement thru the conduit 60 32 under any conditions which might arise.

Said primary and secondary pumps are conveniently driven by the electric motor 34, said motor being conveniently disposed between said pumps and having its shaft ends 65 united therewith by means of the flexible

couplings 35. It is understood, however, that any external means may be applied in driving said pumps.

A dome-like connection 36 is provided to connect the conduit 17 with the return conduit 5, for the purpose of preventing water from passing into the conduit 17.

A conventional base means 37 is conveniently provided in common with the primary and secondary condensers 2 and 7 the primary 75 and secondary pumps 1 and 6, and the electric motor 34.

While I have illustrated in a general way, certain instrumentalities which may be employed in carrying my invention into effect, 80 it is evident that many modifications may be made in the various details, without departing from the scope of the appended claims, it being understood that my invention is not restricted to the particular forms 85 herein described.

I claim as my invention:—

1. A vacuum pump mechanism having a plurality of vacuum operated outlet valves with vacuum operated instrumentalities in communication with the inlet of said mechanism, serving to respond closely to relatively high vacuum tensions, whereby relatively lower degrees of suction in said intake will open one or more of said valves in accordance with such vacuum tensions, whereby intermediate working capacity of the mechanism outlet is automatically maintained, as required.

2. A vacuum pump mechanism having a primary and secondary pump means; primary and secondary condensing means adapted to feed said pump means, respectively; a plurality of vacuum operated valves in communication with the discharge of the secondary pump means, said valves being adapted to be opened with different degrees of vacuum; and a conduit means adapted to communicate the vacuum responding parts of said valves with the intake of the primary pump means, whereby the different degrees of suction in said intake will, under some conditions open all of said valves; under other conditions, close all of said valves and under intermediate conditions open some of said valves.

3. A vacuum pump mechanism having a primary and secondary pump means; primary and secondary condensing means adapted to feed said pump means, respectively; a plurality of vacuum operated valves in communication with the discharge of the secondary pump means, said valves being adapted to be opened with different degrees of vacuum; a conduit means adapted to communicate the vacuum responding parts of said valves with the intake of the primary condensing means whereby the different degrees of suction in said intake will, under some conditions open all of said valves, un-

der other conditions close all of said valves and under intermediate conditions open some of said valves; and a jet means operated by the discharge of the secondary pump 5 means thru said valves, said jets being adapted to suck from the primary condensing means and discharge into the secondary condensing means.

4. A vacuum pump mechanism having a primary and secondary pump means; primary and secondary condensing means adapted to feed said pump means, respectively; a plurality of vacuum operated valves in communication with the discharge of the 15 secondary pump means, said valves being adapted to be opened with different degrees of vacuum; a conduit means adapted to communicate the vacuum responding parts of said valves with the intake of the primary 20 pump, whereby the different degrees of suction in said intake will, under some conditions open all of said valves, under other conditions, close all of said valves and under intermediate conditions open some of said 25 valves; and separate jet means operated by the separate discharges of said valves, said jet means being fed from the primary condensing means and adapted to discharge into the secondary condensing means, when 30 brought into use by the respective vacuum operated parts.

5. A vacuum pump mechanism having a primary and secondary pump means; primary and secondary condensing means adapted to feed said pump means, respectively; a plurality of vacuum operated valves in communication with the discharge of the secondary pump means, said valves being adapted to be opened with different degrees 40 of vacuum; a conduit means adapted to communicate the vacuum responding parts of said valves with the intake of the primary pump means, whereby the different degrees of suction in said intake will, under some 45 conditions, open all of said valves, under other conditions close all of said valves and under intermediate conditions open an intermediate number of said valves; and a dome means adapted to unite said intake 50 with said conduit means.

6. A vacuum pump mechanism having a primary and secondary pump means; primary and secondary condensing means adapted to feed said pump means, respectively, a plurality of vacuum operated valves in communication with the discharge of the secondary pump means, said valves being adapted to be opened with different degrees of vacuum; a conduit means adapted to communicate the vacuum responding parts of said valves with the intake of the primary pump means, whereby the different degrees of suction in said intake will actuate different ones of said valves to vary the capacity 65 of the secondary pump means oppositely

with the increase or decrease of vacuum force in said intake; and a jet means operated by the discharge of the secondary pump means thru said valves, said jet means being adapted to suck from the primary 70 condensing means and discharge into the secondary condensing means.

7. A vacuum pump mechanism having a primary and secondary pump means; primary and secondary condensing means adapted to feed said pump means, respectively; a plurality of vacuum operated valves in communication with the discharge of the secondary pump means, said valves being adapted to be opened with different 75 degrees of vacuum; a conduit means adapted to communicate the vacuum responding parts of said valves with the intake of the primary condensing means, whereby the different degrees of suction in said intake will 80 actuate different ones of said valves to vary the capacity of the secondary pump means reciprocally with the degrees of vacuum in said intake; and separate jet means, the motive streams of which are furnished separately by the discharges of said valves, the intakes of said jet means being fed from the primary condensing means and adapted to discharge into the secondary condensing means, when brought into use by the 85 respective vacuum operated parts. 90

8. A vacuum pump mechanism having a primary and secondary pump means; primary and secondary condensing means adapted to feed said pump means, respectively; a plurality of vacuum operated valves in communication with the discharge of the secondary pump means, said valves being adapted to be opened with different 100 degrees of vacuum; a conduit means adapted to communicate the vacuum responding parts of said valves with the intake of said primary condensing means, whereby the different degrees of suction in said intake will, under some conditions open all of said valves, under other conditions, close all of said valves and under intermediate conditions open an intermediate number of said valves; a jet means operated by the discharge of the secondary pump means thru said valves, 105 said jet means being adapted to suck from the primary condensing means and discharge into the secondary condensing means; and check valve means thru which said discharge passes to said jet means to prevent 110 reversal of the flow. 115

9. A vacuum mechanism having a circulating means; primary and secondary condensing means adapted to feed said circulating means; and a plurality of vacuum operated valves in communication with said circulating means, said valves being adapted to be opened with different degrees of vacuum; a conduit means adapted to communicate the vacuum responding parts of said 125 130

valves with the intake of said circulating means, whereby the different degrees of suction in said intake will, under some conditions, open all of said valves, under other conditions close all of said valves, and under intermediate conditions open an intermediate number of said valves.

10. A vacuum mechanism having a primary and secondary condensing means; a plurality of vacuum operated valves in communication with the outlet of the secondary condensing means, said valves being adapted to be opened with different degrees of vacuum; a conduit means adapted to communicate the vacuum responding parts of said valves with the intake of the primary condensing means, whereby the different degrees of suction in said intake will actuate different ones of said valves to vary the capacity of said outlet oppositely with the increase or decrease of vacuum force in said intake; and a jet means, the motive nozzle of which is communicated with the discharge of said secondary means thru said valves, said jet means being adapted to suck from the primary condensing means and discharge into the secondary condensing means.

11. A vacuum mechanism having a circulating system; primary and secondary condensing means adapted to feed said system; a plurality of vacuum operated valves in communication with the discharge of the secondary condensing means, said valves being adapted to be opened with different degrees of vacuum; a conduit means adapted to communicate the vacuum responding parts of said valves with the intake of the primary condensing means, whereby the different degrees of suction in said intake will actuate different ones of said valves to vary the capacity of said circulating system reciprocally with the degree of vacuum in said intake; and separate jet means the motive streams of which are furnished separately by the discharges of said valves, the intakes of said jet means being fed from the primary condensing means and adapted to discharge into the secondary condensing means, when brought into use by the respective vacuum operated valve parts.

12. A vacuum mechanism having a circulating means; primary and secondary condensing means adapted to feed said circulating means; a plurality of vacuum operated valves in communication with the discharge of the secondary condensing means, said valves being adapted to be opened with different degrees of vacuum; a conduit means adapted to communicate the vacuum responding parts of said valves with the intake of the primary condensing means, whereby the different degrees of suction in said intake will, under some conditions, open all of said valves, under other conditions

close all of said valves and under intermediate conditions open an intermediate number of said valves; a jet means operated by the discharge of the secondary condensing means thru said valves, said jet means being adapted to suck from the primary condensing means and discharge into the secondary condensing means; and check valve means thru which said discharge passes to said jet means to prevent reversal of the flow.

13. A vacuum system having a circulating means; a primary and secondary condensing means adapted to feed said circulating means; a valve means in communication with said circulating means, said valve means being adapted to be influenced openingly with counter-acting force means, and closingly by vacuum force; and a conduit means adapted to communicate the vacuum responding parts of said valve means with the intake of said primary condensing means, whereby a relative lack of vacuum in said intake will tend to allow the counter-acting force means to open said valve means.

14. A circulating system having a primary and secondary condensing means adapted to feed same; a valve means in communication with said system, said valve means adapted to communicate the vacuum responding parts of said valve means with the intake of said primary condensing means, whereby vacuum in said intake, will, under some conditions open said valve means and under other conditions close same; and a jet means, the motive nozzle of which is communicated with the discharge of said secondary condensing means by way of said valve means, said jet means being adapted to suck from said primary condensing means and discharge into the secondary condensing means.

15. In a conduit system, a condensing means in communication with the feed and return lines of said system; and another condensing means adapted to receive from the first mentioned condensing means and discharge into the atmosphere.

16. In a conduit system, a condensing means in communication with the feed and return lines of said system; another condensing means adapted to discharge into the atmosphere; and a jet means, the motive stream of which is fed from the first mentioned condensing means, said jet means being adapted to suck from the first mentioned condensing means and discharge into said other condensing means.

17. A circulating system, having a primary and secondary condensing means adapted to feed same; a valve means in communication with said system, said valve means being adapted to be opened with vacuum force; a conduit means adapted to communicate the vacuum responding parts of said valve means with the intake of said primary con-

densing means, whereby vacuum in said intake will, under some conditions open said valve means and under other conditions close same; and a dome means adapted to unite 5 said conduit means with said intake to prevent liquids from entering said conduit means.

18. A circulating system having a primary and secondary condensing means adapted to 10 feed same; valve means in communication with said system, said valve means being adapted to be influenced openingly with spring counter-balancing means; and closingly by 15 vacuum force; a conduit means adapted to communicate the vacuum responding parts of said valve means with the intake of said primary condensing means, whereby a relative lack of vacuum in said intake will, under some conditions, tend to allow the 20 counter-balancing means to open said valve means, and under other conditions, close same; a jet means, the motive nozzle of which is communicated with the discharge 25 of said secondary condensing means by way of said valve means, said jet means being adapted to suck from said primary condensing means and discharge into the secondary condensing means; and a check valve

means disposed between said primary condensing means and said jet means to prevent 30 reversal of flow.

19. A vacuum pump mechanism having a primary and secondary pumping means, with primary and secondary condensing means adapted to feed said pumping means, respectively; a plurality of vacuum influenced outlet valves in communication with the discharge of said secondary pumping means, the vacuum operated parts of said valves being adapted to respond to different degrees 40 of vacuum and being in communication with the inlet of the primary condenser, whereby the outlet of the secondary pumping means is controlled; and separate jet means operated by the different discharge of said outlet valves, said jet means being fed from the primary condenser when brought into use 45 by the respective vacuum influenced valves for combining the capacity of said secondary pumping means with said primary pumping 50 means automatically, as required.

In testimony whereof, I have hereunto set my hand on this the 28th day of February, 1925, A. D.

WILLIAM P. WHITTINGTON.
